(57) **CLAIM**

The ornamental design for a display screen with application icon, as shown and described.

DESCRIPTION

FIG. 1 is a front view of a display screen with application icon showing the new design enlarged and without the broken line disclosure for clarity of illustration;

FIG. 2 is a front view of the display screen with application icon shown in FIG. 1;

FIG. 3 is a front view of a second embodiment of a display screen with application icon showing the new design enlarged and without the broken line disclosure for clarity of illustration; and,

FIG. 4 is a front view of the display screen with application icon shown in FIG. 3.

The broken-lines shown in FIG. 3 illustrate portions of the second embodiment of the present invention that form no part of the claimed invention. The irregular broken-line perimeter shown in FIGS. 2 and 4 illustrate a display screen and forms no part of the claimed design. The remaining broken lines shown in FIGS. 2 and 4 illustrate portions of a graphical user interface and form no part of the claimed design.
